UNITED STATES PATENT OFFICE.

CLINTON L. BOPP, OF WATERLOO, IOWA.

INDUCTION AUTOMATIC STOP AND CAB-SIGNAL SYSTEM.

1,114,430.

Specification of Letters Patent. Patented Oct. 20, 1914.

Application filed July 26, 1912. Serial No. 711,746.

To all whom it may concern:

Be it known that I, CLINTON L. BOPP, a citizen of the United States, residing at Waterloo, in the county of Blackhawk and 5 State of Iowa, have invented certain new and useful Improvements in Induction Automatic Stop and Cab-Signal Systems; and I do hereby declare the following to be a full, clear, and exact description of the invention, such as will enable others skilled 10 in the art to which it appertains to make and use the same.

This invention relates to improvements in railway signaling systems where the principle of magnetic induction is employed to set into operation mechanism which will indicate the condition of the line.

An object of the invention is to provide a simplified system to break circuits which require no insulation between adjacent blocks 20 and where no current flows except when a train is in the system.

Another object of the invention is to provide a magnetically actuated needle for reducing the resistance of a cab signal circuit 25 so that signal circuits may be closed as the needle is actuated.

With these and various other objects which will appear as the description proceeds, the invention resides in the combination and arrangement of parts shown and described more fully in the following specification and claims.

In the drawings: Figure 1 is a diagrammatic view of a section of railway tracking showing the same divided into four blocks with wiring. Fig. 2 is a similar diagrammatic view showing the track with one train in the system. Fig. 3 is a similar diagrammatic view showing two trains traveling in the same direction. Fig. 4 is a similar diagrammatic view showing two trains in adjacent blocks approaching each other. Fig. 5 is a view, part in elevation and part shown 40 diagrammatically of the locomotive equipment when the same is set to indicate safety. Fig. 6 is a view similar to Fig. 5 showing the locomotive equipment set when the line is in condition of danger. Fig. 7 is a section 45 through a casing in which is mounted an improved time brake setter. Fig. 8 is a fragmentary view showing the location of the magnetic needle relative to the wheel of the locomotive. Fig. 9 shows a modified 50 view of the needle. Fig. 10 shows a detail view of the fuses used in the invention.

view of one of the fuses used in the invention.

This invention depends upon the well known electrical phenomenon that a magnetic needle suspended in a magnetic field set up by current flowing through a wire will be deflected at an angle to the wire. Another fact which is made use of in the present invention is that high potential current will jump the shortest air gap thrust in 60 its path. The general arrangement of the invention is to provide a needle deflected by current flowing in a conductor, a source of high potential current having an air gap in its circuit which is to be regulated by the 65 needle as it swings and certain local circuits designed to be broken as the current flows in the high potential circuit.

In order that the invention may be better understood, the conditions of the track circuits will be traced first.

By referring to Fig. 1, where normal conditions of the track system are shown, it will be seen that rails 1 and 2 are connected respectively to positive and negative poles 80 of a plurality of line batteries, 3, 4, 5, and 6. The rail 1 is connected to the positive poles of the batteries 3, 4, 5, and 6 by means of wires 7, 8, 9 and 10 respectively, and the negative poles are connected to rail 2 by 85 means of wires 11, 12, 13 and 14 respectively. It will be seen from the matter illustrated in Fig. 1 that no current normally flows between the two tracks, or if any current does flow due to leakage it will be so 90 infinitesimal as not to affect the operation of the system. The points where wires 7, 8, 9 and 10 connect with rail 1 define blocks A, B, C and D.

Referring to Fig. 2, it will be seen that 95 train T has been shown as having entered block C, and that a magnetic needle is carried over rail 1 in front of the foremost right wheel, said needle being shown more clearly in Figs. 8 and 9. When the train T is in the position shown all of the batteries in the line will feed through the axles of said train, the batteries 3 and 4 together with all those to the left of 3 feeding through rail 1, and under the needle, while 100 batteries 5 and 6 together with all batteries to the right of battery 6 feed through the axles of train T without passing under the needle. Under these conditions therefore, the batteries in the blocks ahead of the block 105 110

occupied by the train furnish the current which deflects the needle carried by the train.

Referring to Fig. 3, it is assumed that 5 train T has moved to block B and that train T' has entered block C. As in the previous case, current from battery 3 and all the batteries to the left thereof will pass through rail 1 and under the needle and through the 10 axles of train T to the rail 3, and return by the respective return wires. For the reasons pointed out in connection with Fig. 2 current from batteries 5 and 6 together with all the batteries to the right of battery 6 will 15 flow through the axles of the train T' without affecting the needle carried by the train T'. Inasmuch as each of the trains T and T' has a great many axles, the resistance of the path from rail 1 to rail 2 will be so exceedingly low that it may be considered negligible and that the said rails are short-circuited at the point where the wheels contact. With respect to Fig. 3 therefore, it 20 will be seen that the parts of the track extending between the two trains are short-circuited and that no difference of potential exists between the rails 1 and 2 in this part of the track by virtue of either the set of batteries to the left or to the right of the 25 section. The only current which can flow through the rails of the track between the two trains is that furnished by battery 4. Tracing the circuit from battery 4, it will be seen that at the point where wire 8 is 30 connected to rail 1, two paths are open to the current, one of which leads forward to the train T and across to the left hand side of train T, while the other path leads back through rail 1 to train T' across to the other 35 rail 2, and forward to the left hand side of train T. As shown in Fig. 3 it might be estimated that the first of these paths is approximately one-third the length of the second path, it being remembered that the 40 resistance of the train is negligible. Since in a divided circuit current in the various branches will vary inversely as the resistance of those respective circuits, it is obvious that the current through the first of 45 the above circuits will be three times the current in the second circuit traced. It might be considered that the current in wire 50 8 was divided so that three-fourths took the shorter path, whereas one-fourth took the longer path.

Hence, when two trains are traveling in the same direction and are in adjacent blocks, the train ahead will have its needle deflected, while the rear train will be traveling over the track which is carrying current insufficient to operate the needle carried by said rear train.

Referring to Fig. 4, it will be seen that as pointed out in the above paragraph, the battery 65 3 and all batteries to the left thereof

will feed through train T in block B, but inasmuch as train T is moving to the right the current from battery 3 will not effect the needle carried by train T. Similarly, batteries 5 and 6 together with all the batteries 70 to the right of battery 6 will flow through train T' without affecting its needle. As before the current from battery 4 will divide, the lesser current passing through the longer circuit. Inasmuch as the trains are approaching each other, their needles will be located over the divided circuit in which the weaker current is flowing, hence neither of the needles will be deflected, giving the signal to each engineer. Should train T be just 80 in front of the point where wire 7 connects with rail 1, and train T' be just in front of the point where wire 8 connects with rail 1, then, as in the case just described, battery 3 and the batteries to the 85 left thereof will not affect the needle carried by train T. Also, battery 5 and all batteries to the right thereof will not affect the needle carried by train T'. There will be two paths open for the flow of current from battery 4, 90 viz., battery 4, wire 8, over the upper rail of block B, through the train T to wire 12, back to battery, train T being close to the point of contact between wire 12 and rail 2. The other circuit is; battery 4, wire 8, 95 through train T', over the lower rail of block B, up wire 12, and back to battery 4. But these circuits are of substantially equal length, therefore the currents flowing through said circuits are substantially equal. The needles carried by the trains are so 100 designed as not to be deflected far enough when half current flows to keep conditions normal and the needles will therefore tend to align with the rails, as hereinafter described. From these various circuits, it will be seen 105 that when trains are in adjacent blocks and traveling in the same direction, the rear train will be given a signal through its needle, the condition for giving a signal being that the 110 needle shall not be deflected by a current in the rail; and further that if two trains be in adjacent blocks and approaching each other, neither needle will be deflected and both 115 trains will be given a signal.

The magnetic needle associated with the mechanism shown diagrammatically in Figs. 5 and 6 is located just in front of the first right hand wheel of the locomotive looking in the direction of travel. From this it will be seen that when two trains approach each other as shown in Fig. 4, part of the rail which is directly under the needle containing case shown in Fig. 8 is not carrying the normal current necessary to deflect the needle fully, the result of which is to allow needle contained in the case to line up with the rail, which will be described more fully hereinafter.

Referring now to Fig. 5 it will be seen 130

that a section of the rail is indicated at 16, switch 17 being shown in circuit with battery 18 for the purpose of making and breaking circuit through rail 16. This diagrammatic means of showing the making and breaking of circuit through 16 is shown in Fig. 5 as a simple means of sending current through the rail section 16 which condition will necessarily be assumed in describing the 10 operation of the cab circuits. Shown pivotally mounted at 19 is a magnetic needle 20 of greater length than the width of the tread of rail 16, the needle 20 adapted to swing in close proximity to the discharge 15 strip 21. While the magnet has been shown as a single bar, it is to be understood, of course, that said magnet may be of such construction as will render it more sensitive, such as for instance a coil, mounted to 20 swing above the rail, the coil having a discharge point which is adapted to swing in close proximity to strip 21. In either event, the discharge point upon the swinging member is to be provided with platinum 25 or other non-oxidizing metal, which is not readily eaten away by the passage of a high potential spark. If so desired, an astatic couple, such as is illustrated in Fig. 9, may be used as a moving member, the ad- 30 vantage of using said couple being that it is very much more sensitive than a single needle, and therefore would yield to a much weaker current flowing in the rail. Although these various modifications have 35 been referred to, it is to be understood that any needle capable of being deflected by such a current as will normally flow in the rail may be used.

By referring to Fig. 5 it will be seen that 40 two mechanisms aside from the magnetic needle generally indicated at N are shown, the first mechanism being the source of current supply shown at I and the second, a fuse distributing mechanism F. The mechanism I comprises a generator 22 having brushes 23 and 24 mounted upon a shaft 25. There is also mounted upon shaft 25 a commutator 26 having insulated sections 27 and 28, these insulated sections being de- 45 signed to break circuit through brushes 29 and 30 as the generator revolves upon shaft 25. If the moving car upon which the mechanism is located be a steam locomotive a turbo generator set can be used to drive generator 22, while if the mechanism be installed upon an electric locomotive suitable transformations can be made from the line to drive generator 22. In order to take up 50 any sparking which might result at the interrupter as circuit is broken, a condenser 31 is thrown across said brushes. While the mechanism just described furnishes direct current, the induction coil or other high potential apparatus 32 is designed to furnish 55 alternating current of high pressure, pri-

mary 33 of said induction coil being excited from the generator through commutator by the following circuit: Brush 24, wire 34, primary 33, wire 35, brush 30, interrupter 26, brush 29, wire 36, brush 23, back to the 70 commutator of the generator. It will be seen that insomuch as interrupter 26 is inserted in this circuit, the current is continuously interrupted so long as motor 22 revolves, the result of which is to furnish the 75 primary of the induction coil with a fluctuating current, whereby an alternating current is produced in the secondary 33 of said coil.

At F is shown a fuse delivering mechanism provided with a stationary member 37 and a sliding member 38. Stationary member 37 is composed of a housing 39 in which are piled a series of fuses 40, said fuses being of ordinary construction and having 80 metallic ends separated by a strip of insulation, said ends being connected by means of fusible metal carried by the insulation. (See Fig. 10.) Brackets 41 and 42 are rigid with member 37 but insulated thoroughly 85 therefrom, the object of said insulation being to prevent any jumping of current from the secondary of the induction coil to the housing 39. Bracket 41 carries a regulable discharge member 43, while a similar regulable discharge member 44 is carried by bracket 42. A spring contact 45 is carried on the side of the housing 39. The sliding member 38 comprises an insulating base having an upraised portion 46 and having two 90 contact plates 47 and 48 secured to the insulating base. A third contact plate 49 extending the full length of the movable member 38 is provided central of said movable member and serves as a common conductor 95 for current passing through plates 47 and 48. Flexible springs 50 carried by but insulated from stationary member 37 are provided with depending lugs 51 which fit into 100 suitable recesses formed in the metallic ends 105 of the fuses for removing the same, which action will be more fully described hereinafter. For the purpose of clearness, the supports for the springs to the right of 110 Figs. 5 and 6 are removed, but it is to be 115 understood that the supports upon each side of the fuse holder are identical. Part 46 is raised above the contact plates 47 and 48 just enough to retain one of the fuses 40 upon the contact plates as the member 38 120 slides under stationary member 37. Pivoted as at 52 is a lever 53 having a bifurcated end 54 which is designed to engage a pin 55 carried by the movable member 38, which construction admits of the moving of member 38 as the lever 53 swings about pivot 52.

Now that track circuits and part of the mechanism of the locomotive have been described, the circuits resulting from the 130

swinging of the needle 20 will be traced. It will be assumed that the current is flowing in rail 16, that needle 20 is deflected as indicated, and that the fuse delivering mechanism F is in the position shown in Fig. 5. With current flowing in rail 16 it is desired to show that safety will be indicated by the cab equipment. As shown in Fig. 5, current will flow from brush 24, wire 56, electro-magnet 57, wire 58, wire 59, electro-magnet 60, wire 61, contact plate 48, fuse 62, which is good and not blown, contact plate 49, wire 63, wire 64, back to generator by way of brush 23. From this it will be seen that magnet 60 is energized and that as a result armature 65 secured rigidly to lever 53 is attracted to the said electro-magnet. There is also a second circuit contemporaneous with the one just traced which is as follows: Brush 24, wire 56, electro-magnet 57, wire 58, wire 66, electro-magnet 67, wire 68, contact plate 47, the pile of fuses 40, contact plate 49, wire 63, wire 64, back to generator 22 by way of brush 23. Current flowing in this circuit will energize magnet 67 and it will be seen that the air gap between the armature 69 secured rigidly to the lever 53 is greater than that between electro-magnets 60 and armature 65, the natural result of which is that lever 53 will remain in the position shown so long as electro-magnet 60 is energized. The lever 53 carries a spring contact 70 which, as shown in Fig. 5, makes contact with contacting screw 71, which causes the following circuit: Brush 24, wire 56, wire 72, wire 73, contact brush 45, wire 74, lever 53, contact spring 70, contacting screw 71, wire 75, contact 76, armature 77, contact 78, wire 79, electro-magnet 80, wire 81, wire 82, to junction 83, where current divides, part of it going through wire 84, electro-magnet 85, wire 86, wire 87, back to the generator by means of brush 23, and part of it going from the junction 83 to wire 88, white light 89, wire 90, wire 87, back to brush 23 of generator 22. Thus, so long as contact spring 70 engages contact screw 71, a current will be maintained through electro-magnet 85 which controls the brakes of the train and clear light 89.

To explain further the operation of the mechanism it will be assumed that current has failed in the rail 16 under such conditions as are indicated in Figs. 3 and 4, the necessary result of which will be the lining up of the magnet 20 with rail 16. When this is done it will be apparent that the air gap between needle 20 and the strip 21 will be considerably enlarged. The air gap regulator 43 is placed considerably closer to the fuse 91 than air gap regulator 44 is to fuse 62. It will be seen that when air gap 92 is placed in series with variable air gap 93 at the needle, high potential current will pass through wire 94, wire 95, manually operated

switch 96, contact 97, wire 98, strip 21, and will jump gap 93, when needle 20 is as shown in Fig. 5, will pass through the needle 20 to wire 99, down air gap regulator 43, will jump gap 92, will pass to strip 49, wire 63, back to secondary. The sum of the lengths of the air gaps 92 and 93 with needle 20, as is shown in Fig. 5, are designed to be less than air gap 101 which is between air gap regulator 44 and fuse 62. As needle 20 swings, however, the sum of the air gaps 92 and 93 will exceed the length of air gap 101 so that the resistance of the air gap in the circuit containing air gap 101 will be less than the resistance of the air gap of the circuit just traced. Under these conditions the following high potential circuit will be set up: Current will start from secondary 33 of the induction coil, pass through wire 94, wire 102, spark gap regulator 44, air gap 101, plate 49, wire 63, back to the secondary of the induction coil. As shown in Fig. 5 the fusible part of the fuse 62 is directly in the path of air gap 101 so that as current flows in the circuit just traced the fuse will be melted and the circuit containing electro-magnet 60 will be broken. With electro-magnet 60 deenergized and magnet 67 still energized the sliding member 58 will move to the new position indicated in Fig. 6. Insomuch as magnet 67 will attract armature 69 formed rigid with lever 53 the conditions just traced are desired to be accompanied by a signal showing that the line is in condition of danger, such indication being contemporaneous with condition of no current in rail 16. As lever 53 swings to the new position shown in Fig. 6, contact spring 70 will contact with contact screw 100, when the following circuits will be completed: Brush 24, wire 56, wire 72, wire 73, contact spring 45, wire 74, lever 53, spring 70, contact screw 100, wire 103, wire 104, red lamp 105, wire 106, wire 90, wire 87, brush 23, back to generator 22. Current flowing in this circuit will light red light 105, the burning of light 105 being caused by the making of contacts 70 and 100 which necessarily broke contacts 70 and 71. Insomuch as contacts 70 and 71 were in series with electro-magnet 85 and clear light 89, it will be apparent that the latter mentioned devices will be inoperative.

In order to complete the cycle of operation it will be necessary to assume that current is again flowing in rail 16, the natural result of which will be to deflect needle 20 until the same is in the position shown in Fig. 5. The mechanism at F under this consideration will be as shown in Fig. 6, where as the needle will be shown as in Fig. 5. It will be seen that as shown in Fig. 6 the spark gap 92 has interposed therein the fusible part of fuse 91, which fuse is in a good condition. Just as soon as the needle 20 be-

comes close enough to strip 21 to reduce the sum of the air gaps 92 and 93 to a length less than air gap 101 the current will of course take a shorter path and flow through the two air gaps 92 and 93. The flowing of current through air gap 92 and the circuits which have already been traced will result in the fusing of the fuse 91, which fuse is in series with the electro-magnet 67, so that 10 said electro-magnet is deenergized. It will be noted, however, that pile of fuses 40 is under this present consideration in such a position as to make the circuit containing magnet 60 complete, so that said magnet 15 will be energized, the natural result of which is to attract armature 65 and throw the mechanism in the position shown in Fig. 5. So far the description has shown a complete cycle of the signaling apparatus in normal 20 conditions when no bad fuses have been delivered, and when the generator has been generating continuously, and when there is a sufficiency of fuses in housing 39.

If at any time one of the fuses bridging 25 plates 47 and 48 had been blown or a defective fuse had been delivered by the mechanism F, then the path of the circuit leading to the magnets 60 and 67 would have been opened. It will be seen that if the path of 30 magnets 60 and 67 is opened it necessarily follows that magnet 57 will also be opened, the result of which will be the dropping of armature 77, which will close contacts 107 and 108. When this contact is made the following circuit is made: Current will start 35 from brush 24, wire 56, wire 109, contact 107, armature 77, contact 108, wire 140, wire 103, wire 104, red light 105, wire 106, wire 90, wire 87, brush 23, back to generator 22. Thus, it 40 will be seen that in the event of the mechanism F delivering a defective fuse the same will be indicated to the engineer by the lighting of red light 105. Should the dynamo fail to operate, no current will be fed 45 to electro-magnet 85, the result of which will be the deenergization of said magnet with the consequent setting of the brakes to be described hereinafter.

A weight 111 is mounted in housing 37 0 upon the pile of fuses 40 for the purpose of holding said fuses as each successive fuse is taken from the bottom of the pile. Of course a spring could be used for this same purpose, but in either event it would be desirable to have projections 112 carried by the means for pressing the fuses into place, the purpose of which would be to contact, with 55 spring 45 when the fuse supply was low to break contact between spring 45 and wire 60 74 and to make contact between spring 45 and wire 113. When this last mentioned contact is made the following circuit will be completed: brush 24, wire 56, wire 72, wire 73, spring 45, wire 113, wire 104, the red 65 light 105, wire 106, wire 90, wire 87, brush 23, back to the generator 22. Current flowing in this circuit which is closed when the fuse supply has been exhausted or about to be exhausted will light red light 105 which is an indication that part of the mechanism 70 is in need of attention. As shown in either Fig. 5 or 6 a spring ejector 50 provided with a depending point 51 is carried by bracket 41 so that as the swinging member 38 slides under stationary member 37 the 75 point 51 will engage the fuses. To the right of Fig. 5 where the fuse ejecting mechanism is duplicated it will be seen that depending lug or point 51 is in such a position that when member 38 swings the fuse 62 will be carried to the position indicated in Fig. 6. Upon the next oscillation of the fuse delivering mechanism a dead fuse will be carried out by the points of lugs 51 and will force off of the contact strips 48, and 49 the 80 first fuse 62, thereby providing for the automatic ejection of the dead fuses. It is to be borne in mind of course that the contact between the bifurcation 54 and the pin 55 is to be insulated so that no current can pass 85 from lever 53 to the fuse delivering mechanism F.

From the circuits traced it will be seen that magnets 80 and 85 are thrown across generator 22 in series so that if either of 90 said magnets become deenergized it will be accompanied by the simultaneous deenergization of the other. A spring actuated armature 114, suitably pivoted to the frame of the locomotive and provided with a notch 95 115 is designed to be held in an upward position by electro-magnet 80 so long as the said magnet is energized. A spring actuated lever 116, suitably pivoted to the locomotive, is designed to be released by the 100 catch 115 as electro-magnet 80 attracts armature 114. As the lever 116 is released it will be drawn by a spring 117 against a manually operable button 118, by means of which said lever can be made to close contact with contact point 119. Insomuch as the brake setting means, which is operated by electro-magnet 85, is time controlled, it 105 will be possible for the engineer to prevent the setting of the brakes after electro-magnet 115 80 has been deenergized by simply pushing manually operable button 118, which will close the following circuit: brush 24, wire 56, wire 72, wire 120, lever 116, contact point 119, wire 121, wire 82, wire 84, electro-magnet 85, wire 86, wire 87, brush 23, back 120 to generator 22. From the circuit it will be seen that current flowing as indicated will energize electro-magnet 85, a result of which will be to check the mechanisms for setting 125 the brakes.

The mechanism for controlling the brakes, as shown in Fig. 7, comprises electro-magnet 85, pivotally mounted pawl-lever 122, a time controller 123, and a brake 130

valve 124. The pawl-lever 122 pivoted to the frame at 125 has at one end a movable weight 126 for adjusting the balance of the lever so that said end carrying the weight 5 will descend as electro-magnet 85 is deenergized. The other end of the lever 122 which is provided with a catch 127, engages a ratchet wheel 128 rigidly secured to a cam 129 mounted upon shaft 130. 10 Formed integral with cam 129 is a weight 131 the purpose of which is to rotate the cam 129 as pawl-lever 122 is raised from ratchet wheel 128, by descent of weight 126. A suitable opening 132, formed between the 15 weight 131 and cam 129 shows a graduated scale 133 whereby the rate of rotation can be roughly estimated by the engineer. Part of the cam 129 is formed with teeth as at 134, for the purpose of engaging a 20 pinion 135, said pinion carrying with it a fan 136, whereby the descent of weight 131 is restrained from being too rapid. Pivoted to the air brake 124 as at 136 is a screw carrying arm 137 the outer end of which is 25 provided with a roller 138, for engaging cam 129. As the cam 129 rotates under the influence of weight 131, the roller 138 will rest upon the surface 139 of cam 129 until portion 140 arrives under the roller 138, 30 which condition will result in the dropping of arm 137 and the consequent dropping of piston 140 mounted in the air brake casting 124. The valve 141 which is loosely engaged by piston 140 will, as a result of the 35 dropping of piston 140, open a passage between air pipe 142 and exhaust pipe 143. In this way it will be seen that the air brakes may be set by the deenergization of electro-magnet 85 after any desired inter- 40 val of time has elapsed, said time being dependent upon the size of fan 136. Pivoted about shaft 130 is an engineer's lever 144 having mounted therein a rod 145 provided with a teeth engaging point 146 and sliding 45 within said lever 144. A spring 147 carried within lever 144 is designed to hold point 146 normally away from the ratchet wheel 128, but said point may be forced into engagement with said wheel by means of 50 handle 148. After the weight 131 has descended to the stop 149 and the engineer desires to return the weight to its normal position it will be merely necessary for him to depress handle 148 until point 146 engages 55 ratchet wheel 128 and gives the necessary number of oscillations to the lever 144 until said weight 131 has been returned. It will be seen that pinion 135 is provided with a ratchet wheel and pawl 150 so that the en- 60 gineer may return the weight as rapidly as

he wishes, the fan 139 not interfering with the return movement of cam 149.

What I claim is:

1. In a railway signal system, a variable air gap, a source of high potential connected across said air gap, a regulable air gap in multiple with the variable air gap, a fuse located in the regulable air gap, an electric device, a source of current, a closed circuit including the fuse electric device and source of current, and means for varying the length of the variable air gap, the length of the variable air gap adapted at times to exceed the length of the regulable air gap. 65 70

2. In a railway signal system, a source of high potential an electrode connected to one side of said source, a magnetic needle connected to the other side of said source and adapted to have one end thereof swing in proximity to said electrode, an air gap connected in multiple across said electrode and magnetic needle, a closed circuit, a portion of said circuit being fusible and located within the second mentioned air gap, electro magnetic means for deflecting the 80 needle, the distance between the needle and electrode adapted at times to exceed the length of the second mentioned air gap. 85

3. A variable air gap, a regulable air gap, a source of high potential, means for connecting said gaps in multiple across the source of high potential, a closed signaling circuit, a portion of said circuit being fusible and located within the second air gap and means for varying the length of the 90 variable air gap, the variable air gap adapted at times to exceed the length of the second air gap. 95

4. In an electric signaling system, an electric current conductor having magnetic 100 properties, a magnetic needle, an electrode, a source of high potential connecting the electrode and needle, an air gap connected in multiple across the electrode and magnetic needle, a closed circuit, a portion of 105 said circuit being fusible and located within the air gap, said magnetic needle being normally deflected by current passing in the conductor to have one end adjacent the electrode, said needle adapted to align with 110 the conductor when no current is flowing in the conductor the distance between the needle and the electrode under these conditions being greater than the length of the air gap.

In testimony whereof I affix my signature 115 in presence of two witnesses:

CLINTON L. BOPP.
